CLAIM

The ornamental design for a storage basket cart, as
shown and described.

DESCRIPTION

FIG. 1 is a front elevational view of a storage basket
cart showing my new design;

FIG. 2 is a rear elevational view thereof;

FIG. 3 is a left side elevational view thereof, the right
side elevational view being a mirror image of that
shown;

FIG. 4 is a top plan view thereof; and

FIG. 5 is a bottom plan view thereof.

FIG. 1

FIG. 2

FIG.3

FIG.4
